UNITED STATES PATENT OFFICE

162,015

ROTARY FILE

Bernard Discount, Jamaica, N. Y.

Application June 26, 1950, Serial No. 10,760

Term of patent 14 years

(Cl. D74—1)

To all whom it may concern:

Be it known that I, Bernard Discount, a citizen of the United States, residing at Jamaica, in the county of Queens and State of New York, have invented a new, original, and ornamental Design for a Rotary File, of which the following is a specification, reference being had to the accompanying drawing, forming a part thereof.

Fig. 1 is a front elevational view of a rotary file, showing my new design.

Fig. 2 is a top plan view thereof.

Fig. 3 is a side view of one of the sides thereof.

Fig. 4 is a section on line 4—4 of Fig. 1.

The part represented in broken outline is shown for illustrative purposes only.

I claim:

The ornamental design for a rotary file, substantially as shown and described.

BERNARD DISCOUNT.
